UNITED STATES PATENT OFFICE.

EDWIN A. SIMONDS, OF SOMERVILLE, MASSACHUSETTS, ASSIGNOR TO
RIPLEY-HOWLAND MANUFACTURING COMPANY, OF BOSTON, MASSACHUSETTS.

JEWELER'S TOOL.

SPECIFICATION forming part of Letters Patent No. 681,080, dated August 20, 1901.

Application filed March 14, 1901. Serial No. 51,084. (No model.)

To all whom it may concern:

Be it known that I, EDWIN A. SIMONDS, a citizen of the United States, residing at Somerville, county of Suffolk, State of Massachusetts,

5 have invented an Improvement in Jewelers' Tools, of which the following description, in connection with the accompanying drawings, is a specification, like numerals on the drawings representing like parts.

10 In the manufacture of finger-rings it is often desirable to stretch or enlarge a ring after it has been made, so as to increase the diameter thereof; and it is the object of my invention to provide a novel tool for accomplishing this result.

15 My tool comprises a pair of rolls, one of which is preferably smooth-surfaced and is adapted to have a finger-ring slipped over the same, while the other roll has its surface 20 shaped to fit the exterior surface of the ring. One of the rolls is mounted in movable bearings, and suitable adjusting devices are provided whereby the movable bearings may be adjusted to vary the distance between the 25 rolls, so that the rolls may be separated sufficiently to allow of the ring being slipped or inserted over the smooth-surfaced roll, when the adjusting devices may be operated to bring the rolls together, so as to grip the ring 30 therebetween with any desired pressure. Suitable means are provided to rotate the rolls, and such rotation thereof will operate to roll or draw the ring, reducing the cross-sectional area and thus enlarging the diameter 35 thereof. The contiguous faces of the rolls are parallel, and the adjusting devices are so constructed as to maintain the constant parallelism of the said contiguous faces of the said rolls regardless of the distance between the 40 rolls. The device therefore can be utilized on rings of various sizes and of various cross-sectional areas.

45 Referring to the drawings, Figure 1 shows an end elevation of my improved tool. Fig. 2 is a side elevation with parts broken away. Figs. 3 and 4 are details hereinafter to be described, and Fig. 5 is an enlarged view of the non-adjustable roll.

The drawing-rolls between which the ring

is rolled to reduce its cross-sectional area are 50 shown at 3 and 4, the said roll 3 being illustrated as a non-adjustable roll and 4 as an adjustable roll.

55 Preferably I support my rolls upon suitable shafts 5 and 6, the said shafts in this embodiment of my invention being illustrated as parallel shafts and the shaft 5 being mounted in fixed bearings in a suitable housing or frame 7, while the shaft 6 is adjustably mounted therein, as hereinafter described.

60 The frame 7 may be of any usual shape, and, as illustrated, it has the depending lug 8, which may be gripped in a vise or held in any suitable socket in order to rigidly sustain the tool during its operation. The frame 65 has at each end upwardly-projecting arms 9 10, forming between them a suitable slot in which the bearing-block 11 for the adjustable shaft 6 is mounted for vertical movement, and a cap-plate 12, secured to the arms in 70 any suitable way, as by screws 13, sustains the adjusting devices, presently to be described, by means of which the position of the adjustable roll is determined. The shafts which carry the two rolls may be rotated in 75 any suitable way, but I have herein shown the same as provided with the intermeshing gears 14 and 15, and the fixed or non-adjustable shaft 5 will be provided with any suitable crank mechanism 16 by means of which 80 said shaft may be turned, the rotation thereof being communicated to the adjustable shaft 6 by means of the gears 14 15.

85 The rolls 3 and 4 are mounted outside of the frame 7, so that the ring can be easily put on or removed from the non-adjustable roll 3, and in this embodiment of my invention said roll 3 is integral with the shaft 5, the said shaft being projected beyond the frame 7 to form the said non-adjustable roll. It will be 90 obvious, however, that the said roll 3 might be a separate roll rigidly mounted on the shaft, if desired. The adjustable shaft 6 also projects beyond the frame 7 and detachably supports upon its projecting end the adjustable roll 4, 95 the said roll being splined to the shaft, so as to rotate therewith, and being held in place on the shaft by the latch 18, which is pivoted

in any suitable way to the frame and has a slot 19 to engage a groove 20 in the end of the shaft 6.

The adjustable roll 4 is illustrated as having on its periphery grooves 21 of different sizes and shapes to fit the exterior surface of different sized and shaped rings.

In order that the ring may be rolled evenly, it is essential that the axes of the two rolls should always be perfectly parallel at any adjusted position, and I have therefore provided an adjusting device which coöperates with the movable bearing-block 11, which bearing-block extends the full length of the frame, as shown, the said adjusting devices operating constantly to maintain the shafts in parallelism, although at the same time operating to vary the distance between the shafts. The adjusting device is illustrated as comprising two feed-screws 22 23, mounted in the cap-plate 12 and engaging the upper side of the bearing-block 11 at opposite ends thereof, the said screw 22 bearing at its end against the bearing-block and being supported in the cap-plate for longitudinal movement, while the feed-screw 23 is held against movement in the bearing-block and has its lower end screw-threaded, as at 25, said screw-threaded end engaging a screw-threaded socket in the upper side of the bearing-block 11. The screw-threads of the two feed-screws are opposite in pitch, the feed-screw 23 being illustrated as having a right-handed screw-thread, while the feed-screw 22 has a left-handed screw-thread. The upper end of each feed-screw has keyed thereto suitable gears 27 28, respectively, which gears mesh with the drive-gear 29, carried by a pin or post 30, suitably swiveled in the cap-plate and preferably having arms 31 extending therefrom for the convenient manipulation thereof. The feed-screw 22 has a flange 33 thereon, upon which the gear 27 is supported, said gear being keyed to the flange 33 by any suitable keys 60 and being held in place by a suitable nut 34 on the end of said feed-screw. The gear 28 is provided with a hub 35, which rests upon the cap-plate, and the said feed-screw 23 is held from longitudinal movement, as above described, by means of a flange 36 thereon, which engages a suitable shoulder on the under side of the cap-plate, a nut 38 on the upper end of said feed-screw serving to hold the said screw firmly in position.

The operation of the device is as follows: Assuming that the rolls are spread sufficiently to admit of a ring being slipped over the roll 3 in Fig. 1, by turning the spindle 30 to the right the feed-screws 22 and 23 will each be turned in the opposite direction, or to the left, by means of the gears 29 27 28 the feed-screw 22 being advanced downward through the cap-plate 12, and thus bringing together the rolls 3 and 4 to clamp the ring therebetween. The feed-screw 23 will, however, at the same time force the right-hand end in

Fig. 2 of the bearing-block 11 downward, and as the screw-threads on the two feed-screws are of the same pitch and the gears 27 28 are of the same size the result will be that the bearing-block 11 will have a bodily movement toward the fixed shaft, the movable shaft carried thereby being maintained in constant parallelism with the fixed shaft, so that the rolls are brought to bear upon the ring between the same with an even pressure. The crank 16 is then manipulated to turn the coöperating rolls, the said rolls operating to reduce the size of the cross-section of the ring, and thus enlarge the diameter of the same. When a ring which is to have a setting therein is to be enlarged in diameter, the rolls will merely be oscillated, so as to roll or reduce in cross-sectional area that portion of the ring opposite the setting. In rings with settings the thickness of the ring varies slightly from the point directly opposite the setting, where it is thinnest, to a point adjacent the setting, where it is thickest, and in order to compensate for this varying cross-sectional area of the ring and cause the rolls as they are oscillated to bear on the ring with a uniform pressure at every point thereon I preferably make my smooth-surfaced roll slightly eccentric, (see Fig. 5,) the highest point of the roll being opposite the other roll when the handle is in the position illustrated in Fig. 1. In practice the eccentricity of the roll 3 is so small as to be hardly appreciable, for the variation in the cross-sectional area of the ring at different points is very slight, and in Fig. 5 the amount of eccentricity is exaggerated somewhat in the interest of clearness of illustration. With this construction and assuming that the ring is placed between the rolls with its thinnest portion supported on the point of greatest eccentricity of the roll 3 it will be seen that as the crank 16 is vibrated to oscillate the rolls the distance between the contiguous faces of the rolls will vary slightly owing to the eccentricity of the surface of the roll 3, such variation being just sufficient to compensate for the variation in the thickness of the ring. The pressure of the rolls on the ring is therefore the same at every point, and there will be no shoulder made on the ring when the rolling or drawing ceases either side of the setting. When it is desired to remove the ring from between the rolls, the spindle 30 is revolved in the opposite direction or to the left, when the feed-screw 23 will operate to positively lift the right-hand end in Fig. 2 of the bearing-block 11, while the springs 40, which are seated in suitable recesses in the frame and bear against the under side of the bearing-block 11 (see Fig. 3) will operate to raise the left-hand end of the said bearing-block 11 as the feed-screw 22 recedes.

It will thus be seen that I have provided a tool comprising a non-adjustable and an ad-

justable roll, said adjustable roll being carried by an adjustable or movable bearing-block and adjusting devices which operate to separate or bring together the rolls, said adjusting devices operating to maintain the parallelism of the axis of the rolls in any adjusted position thereof.

The object of making the roll 4 detachable is so that different rolls having different shaped grooves in their peripheries may be used as desired for different shapes of rings.

It will be obvious that various changes may be made in the construction of the device without departing from the spirit of my invention—as, for instance, the detachable roll could be mounted upon the shaft 5 instead of upon the adjustable shaft.

Having described my invention, what I claim as new, and desire to secure by Letters

20 Patent, is—

1. In an apparatus of the class described, a shaft mounted in fixed bearings and an eccentric smooth-surfaced roll supported thereon, said roll adapted to have a ring slipped over the same, a parallel shaft mounted in movable bearings, a coöperating roll secured to the end of the last-named shaft, said roll having a working face to fit the exterior of the ring, and means to rotate said shafts in unison, the eccentricity of the smooth-surfaced roll being approximately equal to the difference in thickness of the ring at points directly opposite and adjacent to the setting, whereby as the shafts are rotated the distance between the adjacent surfaces of the rolls varies.

2. In an apparatus of the class described, a shaft mounted in fixed bearings and supporting at one end outside the bearings an eccentric smooth-surfaced roll, said roll adapted to have a ring slipped over the same and the eccentricity of the roll being approximately equal to the difference in thickness of the ring at points directly opposite and adjacent to the setting, a parallel shaft mounted in movable bearings, a coöperating roll detachably secured to said last-named shaft, said detachable roll having a working face to fit the exterior of the ring, means to rotate said shafts, and adjusting devices to vary at will the distance between the shafts, said adjusting devices operating to constantly maintain said shafts in parallelism.

3. In an apparatus of the class described, a frame, a pair of rolls mounted therein, one of said rolls being adjustable, means to rotate said rolls, said adjustable roll being mounted in a single movable bearing-block extending the length of the frame, a screw operating in said frame and impinging at its end against the said bearing-block near one end thereof, a second screw engaging a screw-threaded socket in the other end of said bearing-block, said last-named screw being held against longitudinal movement, and means to

turn the screws, whereby the movable bearing-block is moved bodily to vary the distance between the rolls.

4. In an apparatus of the class described, a frame, a pair of shafts mounted therein for rotation, said shafts carrying rolls at their ends and outside the frame, one of said rolls being adapted to have a finger-ring slipped over the same, and the other roll being shaped to fit the contour of the exterior of the ring, one of said shafts being mounted in a movable bearing-block, means to rotate said shafts, a pair of feed-screws mounted in said frame and engaging said movable bearing-block, one of said screws being mounted in the frame for longitudinal movement, and impinging at its end against said bearing-block, and the other of said feed-screws being held against longitudinal movement, and engaging a screw-threaded socket in the said bearing-block, and means to turn said screws, whereby the distance between the rolls may be varied, said screws operating to constantly maintain the shafts in parallelism.

5. In an apparatus of the class described, a pair of shafts, means to turn the same, co-operating rolls mounted thereon, one of said shafts being mounted in a movable bearing-block, a pair of right and left feed-screws mounted in said frame, one of said screws being mounted in the frame for longitudinal movement, and bearing at its end against the movable bearing-block, and the other of said screws being held against longitudinal movement and engaging a screw-threaded socket in the said movable bearing-block, and means to simultaneously turn said screws in the same direction, whereby the distance between the coöperating rolls may be varied, and the faces of the rolls preserved in constant parallelism.

6. In an apparatus of the class described, a frame, a pair of parallel shafts mounted therein, said shafts carrying coöperating rolls, one of said shafts being supported in a movable bearing-block, a pair of right and left feed-screws mounted in said frame, one of said screws being mounted for longitudinal movement and bearing at its end against the movable bearing-block, the other of said screws being held against longitudinal movement and engaging a screw-threaded socket in the bearing-block, gears at the upper ends of said screws, and means to rotate said gears in the same direction, whereby the distance between the rolls may be adjusted at will and the parallelism of the faces of the rolls preserved.

7. In an apparatus of the class described, a pair of rolls having the contiguous portions of their faces parallel, one of said rolls having an eccentric face the eccentricity of said face being approximately equal to the difference in the thickness of the ring at points directly opposite and adjacent the setting,

means to rotate said rolls in unison and adjusting devices for varying at will the distance between the working faces of said rolls, said adjusting devices operating to maintain the operative portions of the faces of the rolls in parallelism.

In testimony whereof I have signed my

name to this specification in the presence of two subscribing witnesses.

EDWIN A. SIMONDS.
